UNITED STATES PATENT OFFICE.

EDWIN H. ZACHARIAS, OF READING, PENNSYLVANIA.

GARMENT-PRESSING MACHINE.

1,291,344.

Specification of Letters Patent. Patented Jan. 14, 1919.

Application filed August 14, 1917. Serial No. 186,140.

To all whom it may concern:

Be it known that I, EDWIN H. ZACHARIAS, a citizen of the United States, residing at Reading, in the county of Berks and State of Pennsylvania, have invented certain new and useful Improvements in Garment-Pressing Machines; and I do hereby declare the following to be a full, clear, and exact description of the same, reference being had to the accompanying drawings, forming part of this specification, and to the figures and letters of reference marked thereon.

This invention relates to machines for pressing seams of wearing apparel and garments, particularly in the pressing of seams of sleeves and the like, in which the seam is of curved contour and one of the objects of the present invention is the provision of means whereby a sleeve, or similar portion 20 of a garment, can be positioned on the pressing board in such manner that the seam may be pressed throughout its entire length by one continuous stroke of the pressing iron.

The machine adopted for illustrating the present invention is similar to that disclosed in my prior Patent No. 1,115,366, dated October 27, 1914, and is particularly adapted for pressing the seams of trousers, skirts, coats, coat-sleeves and the like. For supporting the garments while being pressed the machine is provided with an ironing or pressing board which projects from a suitable frame work, whereby the garments may be conveniently placed in position on and removed from the free or projecting end of the board, and in connection with the board there is provided means which are adapted for use in pressing seams of curved contour as heretofore stated.

The invention consists in certain novel details of construction and arrangements of parts, all as will be hereinafter described in the preferred form and the novel features thereof pointed out in the appended claims.

Referring to the accompanying drawings,

Figure 1 is a side elevation of a pressing machine embodying the present invention;

Fig. 2 is a bottom plan view of the pressing or ironing board, the means for stretching the seam substantially flat on the pressing board being shown in full lines and the

manner of attaching them to the board, in dotted lines.

Fig. 3 is a transverse section through the 55 pressing board, taken on the line 3—3 of Fig. 1; and

Fig. 4 is an end elevation of the pressing machine.

Like letters of reference indicate the same 60 part throughout the drawings.

The main frame of the machine embodies in its construction a long bed A on which a carriage carrying the iron B travels back and forth. At its ends the bed A is supported by suitable legs or end frames C and at one end it is provided with a forwardly projecting bracket D to which one end of the ironing or pressing board E is rigidly attached by suitable bolts or other approved 65 form of fastening devices. The pressing board E has its upper surface of curved formation in cross section, and in order to make it rigid and unyielding under the pressure of the iron it is preferably backed by two 70 spaced metal bars F, F, between which a longitudinally extending depending portion E' of the board is seated.

In accordance with the present invention the board E is provided on its side opposite 80 the pressing face with yieldable means adapted to be moved toward the board when it is desired to place a garment on the board, as will be presently described, and which will, when the garment is positioned on the 85 board, move away from the board and draw the seam substantially flat on the pressing face. Any yieldable means may be employed for this purpose but in the preferred form, which is illustrated in the accompanying 90 drawings, there is secured to the bottom surface of the portion E' between the bars F, F, by any suitable fastening means, such as screws G, a plurality of elongated resilient strips H, preferably of metal and of such 95 thickness as to be easily flexed or bowed. One end only of each of these strips is thus secured, and they each extend a short distance toward the free end of the pressing board and a portion of each, adjacent their fastened ends, is held close up to the bottom of the board, in the recess between the bars F, F by means of small bolts or cross pieces I journaled in the bars F, F. These strips H

- are then bent or bowed downwardly and back from the cross pieces I toward the opposite end of the board, as shown in Fig. 1, and the free ends attached to a coupling J held close to the bottom surface of the board in a manner to be presently described. A garment upon being placed over the board E to inclose the bowed members H, will be stretched and any irregularities in the width 10 of the garment taken up, thus drawing the seam down substantially flat on the pressing surface of the board so that the seam may be pressed throughout its entire length by one continuous stroke of the pressing iron.
- 15 To hold the ends of the strips H, which are attached to the coupling J, close to the board a chain K is attached to the coupling J and passed over a roller L mounted in the bars F, F. Chain K extends around a roller 20 L' mounted in the frame, thence substantially horizontally over a roller L² mounted in a bracket M attached to the frame work in any suitable manner, and thence downwardly to a foot lever N, one end of which 25 is pivotally mounted in the bracket M. The coupling J and adjacent ends of strips H are free to move longitudinally of the board under the tension of the strips H, which tension tends to bow them and pull the coupling J toward the free end of the board, holding the free end of lever N in elevated position.

- When it is desired to place a garment over the board, the free end of lever N is depressed, pulling the coupling J toward the 35 fixed end of the board and drawing the strips H up close to the bottom of the board. The garment may then be easily slipped over the board and strips and after it has 40 been properly positioned on the board the lever N is released and the members H return to their bowed or flexed position and the garment is consequently drawn substantially flat on the pressing surface of the 45 board.

Preferably, there are a plurality of strips H all positioned in vertical alinement with one another, thus increasing the tension under which the garment is held when 50 placed over the board, but it will be understood that a single strip, or other yieldable member, may be utilized without departing from the spirit of the present invention.

What I claim is:

- 55 1. In a machine for pressing garment seams of curved contour, the combination with a pressing board, of a plurality of resilient metal strips mounted in vertical alinement thereon, said strips being bowed 60 outwardly from said board, whereby a garment placed over said board and strips will be stretched and the seam of the garment drawn substantially flat on said board.

2. In a machine for pressing garment 65 seams, the combination with a pressing

board, of a plurality of resilient metal strips mounted thereon, said strips being bowed outwardly from said board, whereby a garment placed over said board and strips will be stretched and the seam of the garment 70 drawn substantially flat on said board, and means for straightening said strips to permit the garment to be placed over the pressing board and strips.

3. In a machine for pressing garment 75 seams, the combination with a pressing board, of a plurality of flexible metal strips mounted thereon, said strips being bowed outwardly from said board, whereby a garment placed over said board and strips 80 will be stretched and the seam of the garment drawn substantially flat on said board, and means for simultaneously straightening all of said strips to permit the garment to be placed over the board and strips. 85

4. In a machine for pressing garment seams, the combination of the frame, a depending bracket secured to said frame, a pressing board mounted on said frame, a plurality of flexible metal strips mounted on 90 said pressing board, said strips being bowed outwardly from said board whereby a garment placed over said board and strips will be stretched and the seam thereof drawn down substantially flat on the pressing 95 board, a lever fulcrumed in said bracket, and connections intermediate said lever and one end of said strips whereby pressure on one end of said lever will exert a longitudinal pull on the strips and straighten them to 100 permit a garment to be placed over the board and strips.

5. In a machine for pressing garment seams, the combination with a pressing board, of an upwardly yielding garment 105 stretching member below the board and means for moving the said member toward the board and holding the same while a garment is placed in position on the board for pressing. 110

6. In a machine for pressing garment seams, the combination with a pressing board, of a garment stretching member rigidly secured at one end to said board, its central portion being movable at an angle 115 toward and away from the board and means structurally independent of the garment stretching member for moving the central portion of said member toward said board.

7. In a machine for pressing garment 120 seams, the combination with the pressing board, of a yielding garment stretching member having a central portion movable toward and away from the board at an angle with respect thereto, and means for moving 125 the central portion of said garment stretching member toward the board.

8. In a machine for pressing garment 130 seams, the combination with a pressing board, of a yielding garment stretching

member below the board and movable toward and away from the board, said member normally being in position to stretch a garment taut on the board and inherently capable of maintaining such position.

9. In a machine for pressing garment seams, a pressing board, means connected to

the pressing board normally acting to hold taut the seam of an article placed on the board and inherently capable of maintaining its normal position, and means for overcoming the action of said first mentioned means.

EDWIN H. ZACHARIAS.
